ELECTRICAL CIRCUIT INTERRUPTER HAVING
EXTERIOR POSITIONED ACTUATING MEANS
Leon J. Goldberg, Schenectady, N.Y., assignor to General
Electric Company, a corporation of New York
Filed Sept. 6, 1962, Ser. No. 221,755
4 Claims. (Cl. 280—150)

My invention relates to an apparatus for interrupting an electrical circuit and, in particular, to an apparatus for suppressing or extinguishing an electrical arc within a fluid filled sealed container wherein actuated or arc interrupting elements are positioned within the container and actuating means for operating the actuated elements are magnetically coupled thereto and positioned without the container.

Circuit interrupters find use in electrical circuits wherein an interruption of power flow must be achieved in a short interval of time in response to a particular circuit condition. Thus, circuit interrupters are utilized throughout the range of electrical circuitry from electronic circuits operable at less than one watt of electrical power to industrial and utility networks involving thousands of kilowatts of power. Low power circuit interrupters, in general, are characterized by a very small arc formation between the interrupting terminals or contacts of the apparatus during the time interval wherein the electrical circuit is undergoing interruption. The small arc usually presents little difficulty in effecting circuit interruption. However, interruption of higher power circuits, in general, produces a much more extensive arc, and until this arc is completely extinguished, the circuit remains uninterrupted. As a consequence, conventional high power circuit breakers are designed to produce arcs of such dimensions and under such environments that an instability occurs, whereby the arc requires more voltage than the circuit can supply thereby causing the current to decrease.

This instability is usually attained by lengthening the arc between the opened contacts and confining the arc with the aid of arc chutes and arc horns. In direct current circuit interruption, maintaining this kind of instability forces the current to zero, causes arc suppression and extinction, and circuit interruption. Conventional interrupters operating on alternating current circuits do not substantially suppress the arc because it is easier to allow the arc to exist until the alternating current reaches a subsequent zero value and then be prevented from re-establishing itself after the current zero. The arc becomes suppressed when the arc lengthening and confining action has forced the arc to give up more energy than the circuit at the arc voltage can supply. Re-ignition is prevented by operation of a similar structure in promoting deionization between the open contacts to the degree whereat the breakdown gap voltage between the open contacts exceeds the voltage that the circuit will apply thereacross. Air blast or oil blast accessory devices are also often employed to literally blow out the arc by a cooling and arc lengthening or arc dispersing action. At high power levels, arc chutes and arc horns become large, cumbersome, and expensive; air blast accessory devices add further expense; and oil blast accessory devices add both further expense and a fire hazard. Also, during the contact opening interval in conventional high power oil filled circuit breakers, there is generally either a displacement of some of the oil therein or the pressure developed by the oil has a significant effect on the actuating member thereby increasing the circuit interruption time. Since conventional circuit interruption apparatus in the higher power ranges become particularly large and expensive, a need exists for solving this prob-

2

lem by providing a new apparatus for interrupting electrical circuits.

Therefore, one of the principal objects of my invention is to develop a new and improved apparatus for interrupting the flow of power in an electrical circuit.

Another important object of my invention is to develop a new and improved apparatus wherein electrical circuit interruption is developed in a compact sealed chamber.

10 A further important object of my invention is to develop a new and improved apparatus of the electrical circuit interrupting type where in an actuated member is located within a sealed chamber and the actuating member is located without.

15 A still further important object of my invention is to develop a new and improved apparatus for interrupting either direct current or alternating current power wherein the actuated and actuating members are magnetically coupled.

20 Briefly stated, and in accordance with one aspect of my invention in meeting the objects enumerated above, I provide a sealed chamber wherein is disposed an actuated member for developing an arc for the purpose of effecting a circuit interruption. The chamber may be evacuated to a high vacuum or substantially filled with a fluid medium and an actuating member responsive to external circuit conditions is disposed without the chamber and magnetically coupled to the actuated member for the purpose of initiating its operation.

25 30 The features of my invention which I desire to protect herein are pointed out with particularity in the appended claims. The invention itself, however, both as to its organization and method of operation, together with further objects and advantages thereof, may be understood by reference to the following description taken in connection with the accompanying drawing, wherein like parts in each of the several figures are identified by the same reference character, and wherein:

35 FIGURE 1 is an elevation view, partly broken away, illustrating a double break contact and double coil actuating embodiment of a circuit interrupter apparatus constructed in accordance with my invention; and

40 FIGURE 2 is a plan view illustrating the apparatus shown in FIGURE 1.

45 The apparatus of my invention is adapted to combine the principles of both direct current and alternating current power circuit interruption in that it effects suppression of the arc and also prevents re-ignition after a current zero in the alternating current case. Referring particularly to the apparatus illustrated in FIGURES 1 and 2, there is shown a sealed chamber or vessel designated as a whole by numeral 1 wherein the outer surface may have any convenient shape and the inner surface preferably has a hemispherical shape in the upper portion thereof. Chamber 1 comprises two sections, an upper or housing member 2 containing the hemispherical inner surface and a lower or base plate member 3. Housing member 2 is constructed of a strong material, such as steel or iron, in order to withstand the pressures developed within the chamber during arc interruption. Base plate member 3 is made of a non-magnetic metal, such as bronze, brass, or nonmagnetic steel. Housing member 2 is fastened to base plate member 3 by means of several conventional bolt and washer arrangements 4, only one being shown. A gasket type member, such as an O-ring 5 made of rubber, or other suitably plastic and resilient material, assures a pressure type hermetic seal between housing member 2 and base plate member 3. Sealed chamber 1 is connected to a supporting member by means of rod 6, which is fastened to base plate member 3 with a conventional bolt and washer arrangement 7. Rod 6 may comprise any material whereby the rod will adequately support the weight

of the circuit interrupter and is preferably constructed of an electrically insulating material since base plate member 3 may be at line potential. The means for fastening housing member 2 and rod 6 to base plate member 3 is not limited to the bolt and washer arrangement and may comprise any suitable fastening means that achieves a firm joint.

A circuit interrupter actuating means designated as a whole by numeral 8 is positioned without sealed chamber 1 whereas an actuated means designated as a whole by numeral 9 is positioned within. Actuating means 8 is magnetically or inductively coupled to actuated means 9 by means of magnetic inserts 10 which may be made of magnetic steel and comprise a lower portion passing through base plate member 3 and an upper shoulder portion contained within the enclosed chamber. Inserts 10 are intimately and strongly joined to base plate member 3 by any convenient method, such as brazing. Actuating means 8 comprises a pair of cylindrical magnetic core portions 11, as seen in FIGURE 2, which may be manufactured from mild carbon steel, on each of which is wound a coil 12. Coil 12 may be electrically connected in a pushbutton circuit for manual control of circuit interruption or connected to a device which senses abnormal or predetermined circuit conditions for an automatic mode of control. Coil 12 is retained in place on core 11 by magnetic plate 13 on one end thereof and spring washer 14 on the other end with a bolt and washer arrangement 15 passing through magnetic plate 13 and core 11 and into insert 10 to provide a firmly secured magnetic circuit. In the alternative, core 11 may be welded to insert 10, fastened thereto by a stud integral to core 11, or core 11 and insert 10 may comprise a unitary piece, and bolt 15 merely passes into a lower portion of core 11 thereby improving its magnetic properties.

Actuated means 9 comprises a magnetic armature 16 which operates a movable contact 17 into open or closed circuit position with a pair of fixed contacts 18 in response to deenergization or energization of coils 12. It must be understood that the number of fixed contacts in actuated means 9, and coils 12 in actuating means 8 is a matter of design dictated by several considerations which do not affect the principle of this invention. Thus, employing only one fixed contact 18 in a single break circuit within sealed chamber 1 necessitates the use of a flexible conductor that is connected at one end to the movable contact 17 and brought out through the wall of the chamber whereas employing two fixed contacts in a double break circuit requires no flexible conductor and may be brought out of the chamber in a manner to be described in detail hereinafter. The two fixed contact, two-coil embodiment is further preferred since a simple pivot may then be employed for the movable contact. In the preferred embodiment, and as is more clearly illustrated in the plan view of FIGURE 2, actuating means 8 comprises two spaced apart magnetic core legs 11 and magnetic inserts 10 with a separate coil 12 wound on each core leg. Magnetic plate 13 engages both coils 12 and cores 11 thereby completing the magnetic path through core legs 11 and armature 16. Armature 16 comprises a solid body of a suitable magnetic material such as mild carbon steel and has a nonmagnetic shim 19 joined thereto or at the surface of magnetic insert 10 to develop a predetermined air gap in the magnetic path and thereby prevent retention in the closed position by reason of residual flux within core 11. In the closed circuit position, armature 16 extends across and contacts the surfaces of both magnetic inserts 10. An energizing of coils 12 attracts armature 16 electromagnetically or inductively, thereby causing armature 16 to pivot in a clockwise direction about hinge pin 20 and come into contact with the surface of magnetic inserts 10. Two metallic brackets 21 are welded to base plate member 3 and among their functions act as retaining means for hinge pin 20. A second bracket 22 having a generally U-shape in cross section is welded at surface 23 to arma-

ture 16. Thus, when coils 12 are de-energized for purposes of circuit interruption, armature 16 and bracket 22 are caused to pivot about hinge pin 20 in a counterclockwise direction by spring 37 in a manner to be described in detail hereinafter. Fixed contacts 18 comprise two spaced apart copper contacts which may have contact faces of tungsten impregnated with silver or other suitable contact material brazed thereon. Each fixed contact 18 is connected to base plate member 3 by means of an insulation plate 24 and a bolt 26 passing through the base plate, insulation plate, and a portion of the fixed contact. Insulation plate 24 may be composed of a molded or laminated plastic insulation such as filled phenolic resin or other suitable electrically insulating material appropriate to the voltage of the external electrical circuit. A shoulder portion 25 of insulation plate 24 acts as a further aligning means for contacts 18. Bolt 26 is electrically insulated from base plate member 3 by means of bushing 27, made of an electrically nonconductive material. A pressure type hermetic seal connection between fixed contacts 18 and insulation plate 24 and also between insulation plate 24 and base plate member 3 is assured by means of O-rings 28 and 29, respectively, wherein the rings may be made of the same material as O-ring 5. Two power conductors 30, which form part of the electrical circuit being interrupted, are electrically connected to the fixed contacts 18 by means of bolts 26 and electrically insulated from base plate member 3 by means of insulation plate 31 which may be made of the same material as insulation plate 24. In the alternative, bushing 27 and insulation plate 31 may comprise a unitary member. Relatively movable contact 17 is supported on bracket 22 and comprises a body of copper which may also be faced with a suitable electrical contact material and is of sufficient dimension to mate with both fixed contacts 18 when in closed circuit position. Pin 32 having retaining washers on each end thereof passes through a bridging portion 33 of movable contact 17 and through contact supporting bracket 22. The lower washer (not shown) engages bracket 22 on its lower surface and upper washer 34 engages a steel spring 35 maintained under greater compression when in closed circuit position for resilient mounting of contact 17 to effect a positive mating of the face surfaces of contact 17 and contacts 18. An end portion 36 of bracket 22 acts as a guide to maintain alignment of movable contact 17 with stationary contacts 18.

Relatively movable contact 17 is operated into an open circuit position upon de-energization of coils 12 by means of armature 16, bracket 22, spring 37, and stop member 38. Spring 37, having one end engaging contact supporting bracket 22, is in greater compression during the closed circuit position of the contacts as shown by the full lines in FIGURES 1 and 2. Upon de-energization of coils 12, armature 16 is no longer attracted to magnetic inserts 10, and spring 37 thereafter expands thereby pivoting armature 16 and contact supporting bracket 22 in a counterclockwise direction about hinge pin 20 into the open circuit position as shown by the phantom lines in FIGURE 1. Metallic member 39 is welded to the two upstanding portions of bracket 21 and has a recess 40 therein for the guidance of spring 37. The opposite side of spring 37 is retained on bracket 22 by means of a shoulder portion 41. The extent of counterclockwise motion of bracket 22 is limited by stop member 38, the amount of motion being controllable by varying the position of stop member 38 with respect to fixed member 39 in any well-known manner. Thus, by way of illustration, stop member 38 may be connected to fixed member 39 with adjusting screws 42 which are threaded into member 39 and pass through adjusting slots 43 in member 38.

The interior of sealed chamber 1 may contain a vacuum or a fluid, the particular fluid employed being determined by the following considerations. The electrical arc formed on parting of the contacts heats the surrounding fluid and since the fluid cannot escape, it passes through

some or all of the following changes of state: vaporization, decomposition into simpler compounds, decomposition into elements, dissociation, ionization. Since it is desired to regenerate these products back to the original fluid after arc extinction to permit repetitive operation of the circuit interruption apparatus, a fluid that is both dissociable and recombinable must be employed. A fluid comprising a liquid form of a relatively inert gas, such as nitrogen, or an absolutely inert gas such as helium, satisfies the requirements since the single element will return to its original state. Liquid hydrogen may also be employed. A liquid, such as water, splits into hydrogen and oxygen gas which recombines into water due to the prevailing pressure and temperature developed by the arc. The recombination of the hydrogen and oxygen may be further assured by the addition of a catalyst, such as platinum black, placed into the vessel. If the fluid completely fills the chamber and has no dissolved gas or volatile impurity therein, the electrical conduction initiated by an arc formation between opening contacts 17 and 18 takes place within the fluid in liquid form or in a bubble of its gas at a pressure above the critical pressure of the fluid. This condition develops a very high arc voltage and pressure, causing excessively fast circuit interruption which produces undesirable voltage surges. Thus, it is desirable to provide an initial vapor space or its equivalent by displacement wherein the arc may form and be subsequently suppressed and extinguished. The initial vapor space may be provided by not filling sealed chamber 1 completely with the fluid and leaving a very small space therein. Upon arc formation between the contacts 17 and 18, the initial vapor space will be displaced by a gas produced between the conducts due to the arc dissociating the fluid therebetween. By this method circuit interruption is controlled with respect to voltage surge and speed of circuit interruption. Optionally, a collapsible capsule, such as an enclosed bellows arrangement or a piece of sponge rubber or other elastomer with closed pores may be attached to an inner wall of sealed chamber 1 wherein it will not interfere with the operating mechanism, and sealed chamber 1 may be completely filled with fluid. Thus, upon initial arc formation between the parting contacts, the bellows or sponge rubber becomes compressed, thereby providing the necessary vapor space between the contacts for the gas being generated by the dissociating liquid. Further, the fluid may be confined and pressure controlled within sealed chamber 1 by employing a biased or pre-loaded collapsible capsule, such as a sealed spring loaded bellows. In this case, the initial vapor space forms rapidly to a volume determined by the spring pre-loading and then at a retarded rate until the capsule is fully compressed. Thus, a means may be provided for retarding the rate of arc voltage rise either initially on parting the contacts or later as desired.

The liquid which becomes dissociated into high pressure gaseous products between the parted contacts in response to an arc therebetween has the effect of compactly confining the arc within this narrow region defined by high pressure gas. The characteristics of the high pressure gas cause the arc to have a high voltage gradient and to deionize the space between the contacts rapidly after the arc extinguishes. The characteristics of the small volume within which the arc forms cause the arc to develop a high voltage gradient due to the efficient heat transfer to the bounding liquid and to rapidly deionize the corresponding space after arc extinction for the same reason. Thus, these factors of high pressure gas and liquid which is at the same high pressure, and compact confinement of the arc produce an effective arc suppression and effectively prevent re-ignition after arc extinction. The dissociation of the liquid into gaseous products also absorbs energy from the arc, thereby further aiding to suppress it. Thus, a circuit interrupter in accordance with my invention will interrupt compactly both direct current power and greater values of alternating current power as in conventional

interrupter apparatus, since it is easier to deionize gas at current zero than during current flow.

The predetermined vapor space between the parting contacts wherein the arc is produced and suppressed should be controlled as to volume thereof for the most effective interruption characteristics. Hence, it can be appreciated that the prevention of any other net displacement of fluid within vessel 1 due to mechanical actuation is very desirable. Thus, by transmitting the contact actuating forces from an operating magnet on the outside of the vessel through the wall thereof to an armature inside in accordance with my invention, a very efficient interrupter having predetermined interrupting characteristics is obtained. Another advantage of this arrangement is that any pressure developed by the fluid inside the vessel has no primary effect on the work required from the magnet. Further, by placing the actuating means outside the vessel, additional leads need not be brought within the vessel and coils 12 cannot be damaged by the fluid therein.

As a second embodiment of my invention, chamber 1 is evacuated to a high vacuum instead of being filled with a fluid. Interruption under these conditions is effected primarily for alternating current power. When the contacts part, a metallic vapor arc forms which carries current, and at the first subsequent current zero the metallic vapor is very rapidly deionized, dispersed, and condensed in the high vacuum and thus prevents the arc from reforming. The advantage of this apparatus is that a structure can be readily made to include components suitable for high vacuum around the contacts, and a separate actuator that cannot be readily made to be placed in a high vacuum operates the contacts without employing conventional sealed mechanically actuated couplings.

For very high power applications, short arc horns may be attached to the contacts to lengthen the arc, thereby aiding in its suppression. It should be noted that the arc horns used in this application would be considerably shorter than the arc horns necessary in a conventional circuit interrupter apparatus having the same power rating since the arc travels much slower through the confined fluid. Further, a magnetic field may be employed to cause the arc to move on the contacts either along the length of arcing horns provided for this purpose, or to spin repetitively in a circular orbit, to aid in cooling the contacts, and also to cool the arc. The contacts are cooled since the arc movement minimizes the concentration of heating of any one spot on each contact and the arc is cooled since the arc will form in fresh fluid as it advances through the fluid in a manner similar to driving fluid past a stationary arc.

From the foregoing description it can be appreciated that my invention makes available an improved apparatus for the interruption of electrical power wherein an actuating means is located outside of a compact sealed chamber and actuated or circuit interrupting means is located within the chamber which is substantially filled with a dissociable and recombinable fluid or evacuated to a high vacuum. This circuit interrupting apparatus provides a more economical method of circuit interruption than provided by conventional circuit interrupters since the device is very compact especially in the higher power ratings.

Having described two embodiments of a new and improved apparatus for interrupting electrical power circuits, it is believed obvious that modifications and variations of my invention are possible in light of the above teachings. The novel feature of having an actuated means within a sealed chamber and an actuating means without and magnetically coupled thereto, is not limited to the particular embodiment of actuated and actuating means disclosed hereinabove. The particular single movable, double stationary contact, double coil arrangement has been illustrated merely as one example of an actuated and actuating means that may be utilized in my invention and alternative arrangements well known in the art, such as single break contacts and single coils can also be employed. Thus, the

teachings may also be applied to a fuse type of interrupter having fixed contacts or electrodes connected by a fusible link, all confined within the fluid. It is, therefore, to be understood that changes may be made in the particular embodiment of my invention described which are within the full intended scope of the invention as defined by the following claims.

What I claim as new and desire to secure by Letters Patent of the United States is:

1. A compact electrical circuit interrupter comprising 10 a base plate member,

actuated means comprising a relatively movable contact, a pair of stationary contacts, and a magnetic armature for operating said movable contact into open and closed circuit position with said stationary contacts,

a totally enclosed compact container,

a dissociable fluid confined within said container, said actuated means positioned within said container and immersed within said fluid, said fluid dissociating into 20 a gaseous medium in a region between the contacts in response to production of an electric arc therebetween, said gaseous medium forming at high pressure by reason of a fixed volume of fluid and gas in said vessel whereby the arc becomes extinguished and thereby interrupts the electrical circuit, said gaseous medium thereafter recombining in absence of the arc to form the original fluid, and

actuating means for operating said actuated means and magnetically coupled thereto, said actuating means 30 disposed without said container and comprising two spaced apart magnetic core legs and coils wound thereon,

magnetic inserts joined to each core leg, said inserts including a first portion passing through said base plate member and a shoulder portion contained within said container,

a nonmagnetic shim positioned between the shoulder portion of said inserts and said armature whereby said nonmagnetic shim is in contact with said shoulder portion and said armature during closed circuit position of said movable and stationary contacts to develop a predetermined air gap in the magnetic path and thereby prevent retention of said movable contact in the closed circuit position by reason of residual flux in said core legs, energization of said coils causing said armature to pivot and thereby communicate with said magnetic inserts to move said movable contact into closed circuit position.

2. An electrical circuit interrupter comprising a base 50 plate member,

actuated means for opening and closing an electrical circuit, said actuated means comprising

a pair of stationary contacts and a relatively movable contact, said relatively movable contact having two 55 contact making surfaces and a bridging portion therebetween,

a magnetic armature for operating said movable contact into open and closed circuit position with said stationary contacts,

a hinge pin in communication with one end of said armature for pivoting said armature,

first bracket means connected to said base plate member for retaining said hinge pin,

a second bracket connected to said armature, said relatively movable contact supported on said second bracket, said second bracket having an end portion to maintain alignment of said movable contact with said stationary contacts,

a spring having one end thereof supported on said second bracket, said spring in greater compression during closed circuit position of said movable and stationary contacts, said spring expanding upon deenergization of coils in an actuating means for said interrupter thereby pivoting said armature and said second

70
75

bracket about said hinge pin to operate said movable contact into open circuit position,

a hermetically sealed compact container, a dissociable fluid confined within said container, said actuated means positioned within said container and immersed within said fluid, said fluid dissociating into a gaseous medium in a region between the contacts in response to production of an electric arc therebetween, said gaseous medium forming at high pressure by reason of a fixed volume of fluid and gas in said vessel whereby the arc becomes extinguished and thereby interrupts the electrical circuit, said gaseous medium thereafter recombining in absence of the arc to form the original fluid, and actuating means for operating said actuated means and inductively coupled thereto, said actuating means disposed outside said container.

3. An electrical circuit interrupter comprising a base plate member,

actuated means for opening and closing an electrical circuit, said actuated means comprising a pair of stationary contacts and a relatively movable contact, said relatively movable contact having two contact making surfaces and a bridging portion therebetween,

a magnetic armature for operating said movable contact into open and closed circuit position with said stationary contacts,

a hinge pin in communication with one end of said armature for pivoting said armature,

first bracket means connected to said base plate member for retaining said hinge pin,

a second bracket connected to said armature, said relatively movable contact supported on said second bracket, said second bracket having an end portion to maintain alignment of said movable contact with said stationary contacts,

a spring having one end thereof supported on said second bracket, said spring in greater compression during closed circuit position of said movable and stationary contacts, said spring expanding upon deenergization of coils in an actuating means for said interrupter thereby pivoting said armature and said second bracket about said hinge pin to operate said movable contact into open circuit position,

a sealed compact vessel, said actuated means disposed within said vessel,

a dissociable and recombinable fluid substantially filling said vessel, said actuated means immersed within said fluid, and

actuating means for operating said actuated means and inductively coupled thereto, said actuating means disposed without said vessel and comprising

two spaced apart magnetic core legs and coils wound thereon,

magnetic inserts joined to each core leg, said inserts including a first portion passing through said base plate member and a shoulder portion contained within said vessel,

a nonmagnetic shim positioned between the shoulder portion of said inserts and said armature whereby said nonmagnetic shim is in contact with said shoulder portion and said armature during closed circuit position of said movable and stationary contacts to develop a predetermined air gap in the magnetic path and thereby prevent retention of said movable contact in the closed circuit position by reason of residual flux in said core legs, energization of said coils causing said armature to pivot about said hinge pin and thereby communicate with said magnetic inserts to move said movable contact into closed circuit position.

4. A compact electrical circuit interrupter comprising a base plate member,

actuated means for opening and closing an electrical circuit, said actuated means comprising a pair of stationary contacts and a relatively movable contact, said relatively movable contact having two contact making surfaces and a bridging portion therebetween, 5 a magnetic armature for operating said movable contact into open and closed circuit position with said stationary contacts, a hinge pin in communication with one end of said 10 armature for pivoting said armature, first bracket means connected to said base plate member for retaining said hinge pin, a second bracket connected to said armature, said movable contact supported on said second bracket, said 15 second bracket having an end portion to maintain alignment of said movable contact with said stationary contacts, a second pin having retaining means on each end thereof, said second pin passing through the bridging 20 portion of said movable contact and through said second bracket in engaging relationship thereto at a first end thereof, a first spring engaged by a second end of said second 25 pin and maintained under greater compression during closed circuit position of said movable and stationary contacts for resilient mounting of said movable contact to effect positive mating of the contact making surfaces of said movable and stationary contacts, 30 a second spring having a first end thereof supported on said second bracket and a second end retained in a fixed position by means of a recessed member joined to said first bracket, said second spring in greater compression during closed circuit position of said 35 movable and stationary contacts, said second spring expanding upon deenergization of coils in an actuating means for said interrupter thereby pivoting said armature and said second bracket about said hinge pin to operate said movable contact into open circuit 40 position, a sealed compact chamber, said actuated means disposed within said chamber,

a medium contained within said chamber, said medium being different from the outside atmosphere, and actuating means for operating said actuated means and magnetically coupled thereto, said actuating means disposed without said chamber and comprising two spaced apart magnetic core legs and coils wound thereon, magnetic inserts joined to each core leg, said inserts including a first portion passing through said base plate member and a shoulder portion contained within said chamber, a nonmagnetic shim positioned between the shoulder portion of said inserts and said armature whereby said nonmagnetic shim is in contact with said shoulder portion and said armature during closed circuit position of said movable and stationary contacts to develop a predetermined air gap in the magnetic path and thereby prevent retention of said movable contact in the closed circuit position by reason of residual flux in said core legs, energization of said coils causing said armature to pivot about said hinge pin and thereby communicate with said magnetic inserts to move said movable contact into closed circuit position.
